UNITED STATES PATENT OFFICE.

EUGENE J. HOLZER, OF MILWAUKEE, WISCONSIN, ASSIGNOR TO MILWAUKEE LACE PAPER COMPANY, OF MILWAUKEE, WISCONSIN, A CORPORATION OF WISCONSIN.

DESIGN FOR A DOILY.

Application filed September 16, 1922. Serial No. 3,738. Term of patent 14 years.

To all whom it may concern:

Be it known that I, EUGENE J. HOLZER, a citizen of the United States, residing at Milwaukee, in the county of Milwaukee and State of Wisconsin, have invented a new, original, and ornamental Design for a Doily, of which the following is a specification, reference being had to the accompanying drawing, forming a part thereof.

The figure is a top plan view of the doily, showing my new design.

I claim:

The ornamental design for a doily, as shown.

EUGENE J. HOLZER.
